UNITED STATES PATENT OFFICE

ARTHUR GUY ENOCK, OF WEMBLEY PARK, ENGLAND, ASSIGNOR TO BURLECTAS LIMITED, OF LONDON, ENGLAND

BOTTLE CRATE

Application filed May 31, 1930, Serial No. 457,970, and in Great Britain August 13, 1929.

This invention relates to metal crates for bottles the sides and ends of which are made from stamped plates of thin sheet metal—more particularly adapted for milk bottles—in which the bottles can be placed for transport and in which they may be treated for washing, sterilizing, drying and filling and the subsequent operation of sterilizing the contents.

10 According to the invention the thin sheet metal walls (sides and ends) of the crate are constructed with inwardly pressed panels to project into the interior to give strength to the walls and to position the outer rows of 15 bottles or vessels therein presenting a smooth outer surface free of projections, longitudinal transverse and vertical division wires to form spaces for and separate the bottles or vessels being welded in the interior.

20 The invention will be fully described with reference to the accompanying drawings:— Fig. 1 is a longitudinal sectional elevation of improved crate.

Fig. 2 is a transverse sectional elevation.

25 Fig. 3 is a plan partly in section.

Fig. 4 is a modification showing the vertical guide wires bent at an angle.

Fig. 5 is a perspective view of wires welded together into a cage.

30 Figs. 6 and 7 are modifications showing part plans of pressed metal frame to replace the top and bottom dividing wires.

Fig. 8 is a longitudinal section of pressed metal bottom frame.

35 Fig. 9 is a longitudinal section of another form of pressed metal frame.

The crate is made with four walls, two side plates A and two end plates A¹ of thin sheet metal preferably steel. Each wall is

40 made with four or five panels a (more or less according to the size of the crate or bottle) inwardly pressed to project towards the interior of the crate to stiffen or strengthen the wall and position the bottles. The edges a¹ of the plates A are pressed or bent over at right angles to lap over at the corners when assembled together and are welded thus forming stiff strong vertical corners to the crate. The side plates A preferably over-lap

45 the end plates A¹ to the outsides. Reinforc-

ing members B such as angle strips or rods are welded or otherwise affixed around the top and bottom edges of the walls preferably inside to stiffen and strengthen them or instead of such reinforcing members the edges 55 may be flanged or folded over or beaded to give the desired strength or stiffness.

Hand holes or apertures C are made in the end plates with their edges turned or curved inwards.

The walls and the panels may be made with a number of apertures or perforations a² at intervals to lighten them.

The wires D at the bottom of the crate on which the bottles rest are bent at right angles 65 at their ends and are welded to the interior surface of the inwardly projecting side panels a. The longitudinal horizontal division wires E and F and the transverse horizontal dividing wires G and H at right angles to 70 each other at the top and bottom of the crate which forms the divisions for the bottles are bent at right angles at their ends and are welded to the end and side walls between the panels a.

75 The bending of the ends of the division wires at right angles gives a greater bearing and welding surface against the walls, forms a stronger joint and provides for expansion and contraction of the wires after welding 80 and also during use.

Vertical guide wires K are welded between the longitudinal division wires E and F and vertical guide wires K¹ between the transverse wires G and H to guide the bottles into 85 position the wires K and K¹ being spaced midway between the points of crossing of the wires E and G. The wires E and G and the wires F and H are also preferably welded together at their points of crossing.

90 The horizontal division wires E, F, G, H and the vertical guides wires K, K¹ may be made separately into the form of a cage by welding in the vertical guide wires K K¹ and then welding the longitudinal and transverse 95 division wires E and G and F and H together in jigs to accurate dimensions. The cage so formed see Fig. 5 is placed in position in the crate and welded to the walls by the bent up and down ends of the wires. The ends of the 100

vertical guide wires K K¹ may also be bent to give a larger welding surface.

The cage of wires E, F, G, H, K, K¹ when welded in position greatly strengthens and stiffens the walls and increases the rigidity and durability of the crate.

As a modification in substitution for the longitudinal and transverse horizontal division wires E, F and G, H, a pressed or stamped sheet metal frame with cross members E¹ such as shown in Figs. 6 to 9 may be fitted into the interior above and below the panels *a* and secured by welding or other means. The bottom frame may also be provided with transverse bottle supporting members D¹.

Reinforcing or strengthening members B are fitted into and welded to the top and bottom edges of the side and end plates of the crate.

Stacking irons N are welded at the corners to the top reinforcing members M to maintain the crates in position when stacked one upon the other and strengthen the corners of the crate and assist in keeping the crate in shape.

What I claim as my invention and desire to protect by Letters Patent is:—

1. A metal crate for bottles comprising thin sheet metal plates forming the side and end walls, panels pressed inwards from the metal sheets and an interior cage welded to the walls, horizontal wires forming the top and bottom of the cage and vertical guide wires welded to both top and bottom to divide the cage into compartments and connect the top to the bottom.

2. A metal crate for bottles comprising thin sheet metal plates overlapped and welded at the corners forming the side and end walls, panels pressed inwards from the metal sheets and an interior cage welded to the walls, longitudinal and transverse horizontal wires welded together at each point of intersection to form the bottom of the cage, further horizontal wires upon which the bottles rest welded at each point of intersection to the first mentioned horizontal wires, longitudinal and transverse horizontal wires welded together at each point of intersection to form the top and vertical guide wires connecting the top to the bottom and welded to both.

3. A metal crate as in claim 2 in which the longitudinal and transverse horizontal wires are bent over at their ends before welding to the walls.

4. A metal crate for bottles comprising thin sheet metal plates overlapped and welded at the corners forming the side and end walls, reinforcing members welded to the walls around the top and bottom edges, panels pressed inwards from the metal sheets and an interior cage welded to the walls, longitudinal and transverse horizontal wires welded together at each point of intersection to form the bottom of the cage, further horizontal wires upon which the bottles rest welded at each point of intersection to the first mentioned horizontal wires longitudinal and transverse horizontal wires welded together at each point of intersection to form the top and vertical guide wires connecting the top to the bottom and welded to both.

In testimony whereof I have hereunto set my hand this 19th day of May, 1930.

ARTHUR GUY ENOCK.
